UNITED STATES PATENT OFFICE.

ALBERT O. BUCKIUS, JR., OF CHICAGO, ILLINOIS, ASSIGNOR TO THE NATIONAL MALLEABLE CASTINGS COMPANY, OF CHICAGO, ILLINOIS, A CORPORATION OF OHIO.

RAIL-ANCHOR.

No. 831,140.

Specification of Letters Patent.

Patented Sept. 18, 1906.

Application filed June 14, 1906. Serial No. 821,662.

To all whom it may concern:

Be it known that I, ALBERT O. BUCKIUS, Jr., of Chicago, Cook county, Illinois, have invented a new and useful Rail-Anchor, of which the following is a full, clear, and exact description, reference being had to the accompanying drawings, forming part of this specification, in which—

Figure 1 is a central vertical section showing one form of my improved rail-anchor applied to a rail. Fig. 2 is a side elevation of the same. Fig. 3 is a modification, partly in section and partly in end elevation. Fig. 4 is a detail view, and Fig. 5 is a detail view of the wedge.

On railways having two or more tracks in which the cars on the several tracks do not travel in the same direction there is a tendency of the rails to creep lengthwise on the ties in the direction of travel. The devices which have heretofore been proposed for preventing such creeping, in so far as I am aware, have been unsatisfactory on account of their complexity and because of the difficulty of properly tightening and holding them to the rail after they have become loosened by the jarring and corrosion of the parts to which they are especially subjected.

The present invention is designed to overcome these difficulties and provides an anti-creeping anchor which is of cheap and simple construction, which can be readily and securely applied to the rail, and which can be quickly and readily tightened should it become loose in service.

With these objects in view my invention consists in the novel construction, arrangement, and combination of parts, all substantially as hereinafter described, and pointed out in the appended claims.

In the accompanying drawings the numeral 2 designates a bar or base-piece which is arranged to extend transversely underneath the base of the rail from one side to the other and having at one end an integral jaw 3, which embraces the edge portion of the base of the rail and which at its opposite end carries a movable jaw 4, which embraces the opposite edge of the base of the rail. The jaw 4 is of stirrup or loop form and is seated on the base 2, between the flanges 5 and 6 thereof, and securely held up in place. The upper

surface of the base-piece at its end is inclined at 3^a to form a bearing-surface for the correspondingly-inclined surface of a tightening-wedge 7, which is seated thereon, and is formed with the lugs 8, which hold it against lateral movement. The wedge is perforated to receive a bolt 9, which is seated in the base 2, the outer end of the bolt being provided with a clamping-nut 10, which bears against the outer end of the wedge. By screwing this nut against the wedge the latter is forced up the inclined surface 3^a of the base against the under side of the rail-base. Any looseness which may be developed at any time can be readily taken up by simply tightening this nut. The upper face of the wedge is preferably provided with a corrugated insert 11 of hard metal for engagement with the rail-base, the corrugations being in the form of teeth, which engage the base of the rail and hold the rail securely. The base portion 2 is formed with a depending projection 12, having a lateral strengthening-rib 13 and designed to bear against the side of the tie, and thereby form a stop by means of which creeping of the rail is prevented.

In the modification shown in Fig. 3 instead of forming the base-piece 2 with an integral jaw at one end I provide the base with two separate jaws 4^a and 4^b, each of which is similar to the separate jaw in the construction first described and each of which is provided with a tightening-wedge 7^a, similar to the wedge of Fig. 1. Both these wedges are engaged by through-bolt 14, having a head 15 at one end bearing against the outer end of one of the wedges and a clamping-nut 16 at the other end bearing against the outer face of the other wedge. By screwing up this nut both the wedges are simultaneously tightened.

The manner in which the device is applied to the rail will be readily understood from Fig. 1.

The device may be modified in various ways without departing from the spirit and scope of my invention, since

What I claim is—

1. A rail-anchor having a base-piece extending under the base of the rail and provided with a jaw at one end, and with a depending portion mounted at the opposite end

- portion of the base-piece, and a wedge device arranged to engage the under side of the base of the rail; substantially as described.
2. In a rail-anchor, a base-piece having a jaw thereon and a depending projection, and a wedge device seated on the base-piece and arranged to pass underneath the base of the rail; substantially as described.
3. In a rail-anchor, a base-piece having a depending projection and a movable jaw engaged therewith, a wedge member seated between the base-piece and the base of the rail, and means for adjusting the wedge member; substantially as described.
- 15 4. A rail-anchor having a base member formed with an inclined surface, a wedge movable on said surface against the base of the rail, and a jaw seated on the base member and engaged by the wedge; substantially as described.
- 20 5. A rail-anchor having a base-piece formed with a depending stop projection, and having rail-engaging jaws thereon, at least one of said jaws being movable, and a wedge device arranged to engage the base of the rail; substantially as described.
- 25 6. A rail-anchor consisting of a base-piece having a depending projection, rail-holding jaws seated upon each end portion of the base-piece, and arranged to hold the rail-base, wedge members seated on the base-
- piece, and engaging the jaws, and means for moving the wedges; substantially as described.
7. In a rail-anchor, a base member having a depending stop portion and inclined surfaces at its ends, wedges movable on the inclined surfaces, rail-engaging jaws engaged with the base member and engaged by the wedges, and means for tightening the wedges; substantially as described.
8. A rail-anchor having a base-piece formed with a depending stop projection and having transversely-movable wedges seated on its end portions, and jaws engaging the base member and engaged by the wedges, together with means for moving the wedges; substantially as described.
9. A rail-anchor, consisting of a base-piece having a depending projection to bear against a rail-tie, a stirrup mounted on the base-piece and having a jaw to hold the flange of the rail, and a gripping-wedge arranged to have a biting contact with the bottom of the rail; substantially as described.
- 50 In testimony whereof I have hereunto set my hand.
